US0D1054030S

(12) **United States Design Patent** (10) **Patent No.:** **US D1,054,030 S**
(45) **Date of Patent:** **** Dec. 10, 2024**

(54) **ULTRASONIC SCALPEL**

- (71) Applicant: **INNOLCON MEDICAL TECHNOLOGY (SUZHOU) CO., LTD.**, Suzhou (CN)
- (72) Inventors: **Zhongyu Yan**, Jiangsu (CN); **Lei Wang**, Jiangsu (CN); **Wei Luo**, Jiangsu (CN)
- (**) Term: **15 Years**

(21) Appl. No.: **35/515,069**

(22) Filed: **Jun. 30, 2022**

(80) **Hague Agreement Data**

- Int. Filing Date: **Jun. 30, 2022**
Int. Reg. No.: **DM/223031**
Int. Reg. Date: **Jun. 30, 2022**
Int. Reg. Pub. Date: **Sep. 2, 2022**
- (51) **LOC (14) Cl.** **24-02**
(52) **U.S. Cl.** **D24/146**
- (58) **Field of Classification Search**
USPC D24/133, 130, 112, 144–148; D8/101,
D8/98, 47

Primary Examiner — Justin M Jonaitis
Assistant Examiner — Holly M Rodriguez

(57) **CLAIM**

The ornamental design for ultrasonic scalpel as shown and described.

DESCRIPTION

- 1.1** : Front
1.2 : Back
1.3 : Enlarged left
1.4 : Enlarged right
1.5 : Top
1.6 : Bottom
1.7 : Perspective
1.8 : Enlarged perspective of section A
1.9 : Enlarged front of section A
1.10 : Enlarged back of section A
1.11 : Enlarged top of section A
1.12 : Enlarged bottom of section A
2.1 : Front
2.2 : Back
2.3 : Enlarged left
2.4 : Enlarged right
2.5 : Top
2.6 : Bottom
2.7 : Perspective
2.8 : Enlarged perspective of section B
2.9 : Enlarged front of section B
2.10 : Enlarged back of section B
2.11 : Enlarged top of section B
2.12 : Enlarged bottom of section B
3.1 : Front
3.2 : Back
3.3 : Enlarged left

(Continued)

- 3.4 : Enlarged right
 3.5 : Top
 3.6 : Bottom
 3.7 : Perspective
 3.8 : Enlarged perspective of section C
 3.9 : Enlarged front of section C
 3.10 : Enlarged back of section C
 3.11 : Enlarged top of section C
 3.12 : Enlarged bottom of section C
 4.1 : Front
 4.2 : Back
 4.3 : Enlarged left
 4.4 : Enlarged right
 4.5 : Top
 4.6 : Bottom
 4.7 : Perspective
 4.8 : Enlarged perspective of section D
 4.9 : Enlarged front of section D
 4.10 : Enlarged back of section D
 4.11 : Enlarged top of section D
 4.12 : Enlarged bottom of section D
 5.1 : Front
 5.2 : Back
 5.3 : Enlarged left
 5.4 : Enlarged right
 5.5 : Top
 5.6 : Bottom
 5.7 : Perspective
 5.8 : Enlarged perspective of section E
 5.9 : Enlarged front of section E
 5.10 : Enlarged back of section E
 5.11 : Enlarged top of section E
 5.12 : Enlarged bottom of section E
 6.1 : Front
 6.2 : Back
 6.3 : Enlarged left
 6.4 : Enlarged right
 6.5 : Top
 6.6 : Bottom
 6.7 : Perspective
 6.8 : Enlarged perspective of section F
 6.9 : Enlarged front of section F
 6.10 : Enlarged back of section F
 6.11 : Enlarged top of section F
 6.12 : Enlarged bottom of section F
- These designs are for ultrasonic scalpels used for hemostatic cutting of tissue and/or coagulation and sealing of blood vessels.

The broken lines in the drawings illustrate portions of the ultrasonic scalpels which form no part of the claimed design.

1 Claim, 72 Drawing Sheets
